UNITED STATES PATENT OFFICE.

FRED F. JENNINGS, OF KANSAS, ILLINOIS.

TUG-LOOP.

No. 872,067.

Specification of Letters Patent.

Patented Nov. 26, 1907.

Application filed May 13, 1907. Serial No. 373,438.

To all whom it may concern:

Be it known that I, FRED F. JENNINGS, a citizen of the United States, residing at Kansas, in the county of Edgar, State of Illinois, 5 have invented certain new and useful Improvements in Tug-Loops; and I do hereby declare the following to be a full, clear, and exact description of the invention, such as will enable others skilled in the art to which 10 it appertains to make and use the same.

This invention relates to new and useful improvements in tug loops and has particular reference to a tug loop constructed of sheet metal and including a roller which 15 serves as a guide for the tug as the latter works back and forth in use, the object being to provide a novel construction, combination and arrangement of parts.

The details of the invention will appear in 20 the course of the following description in which reference is had to the accompanying drawings forming a part of this specification, like characters of reference designating similar parts throughout the several views, 25 wherein:

Figure 1 is a developed plan view of the blank from which the tug loop comprehended in the present invention is formed. Fig. 2 is 30 a view showing the tug loop in use in connection with ordinary harness. Fig. 3 is a side elevation of the tug loop. Fig. 4 is a vertical transverse sectional view thereof.

Referring specifically to the accompanying drawings, the numeral 1 designates a 35 sheet metal blank formed with a central rectangular opening 2. The blank 1 is bent into such conformation that the material at the sides of said opening affords loops 3. Beyond said opening, the blank 1 is bent 40 along the dotted lines 4 to afford horizontal offsets 5, the material between the end edges of said opening and the lines 4 being extend-

ed in parallelism from the loops 3 as indicated at 6 to afford a narrow neck. Beyond the offsets 5, the material of the blank 1 is 45 again bent to afford spaced parallel enlarged ears 7, which practically form the body portion of the loop. Between the lower ends of the ears 7 is a suitable transverse pin 8, upon which is mounted a tug roller 9. The loops 50 3 are formed to loosely surround a pin 10 disposed at a right angle to the pin 8 and affording a pivotal suspension for the tug loop as an entirety. The pin 10 is carried by each of the straps 11, which depend from the harness 55 saddle.

The tug, designated by the letter A is passed between the ears 7 and bears against the roller 9, the shoulders 5 preventing play thereof, such as would tend to throw the 60 same off the roller 9 and cause a wedging or binding of the parts.

The tug loop comprehended in the present invention is designed to reduce wear on the finished part of the harness and the shaft, 65 and likewise to eliminate friction.

The device is simple in construction, inexpensive to manufacture, and practical and efficient in use.

What is claimed is:

A device of the type set forth comprising a 70 sheet metal blank having a central rectangular opening and bent to form the material at each side of said opening as loops, the material at each end of said opening being offset 75 and bent in spaced parallel relation to afford ears, a pin held between said ears, and a roller mounted upon said pin.

In testimony whereof, I affix my signature, in presence of two witnesses.

FRED F. JENNINGS.
